UNITED STATES PATENT OFFICE.

THOMAS LANGHAM, OF PHILADELPHIA, PENNSYLVANIA, ASSIGNOR TO
THOMAS DOLAN AND R. WILLIAMS, JR., OF SAME PLACE.

DESIGN FOR KNITTED FABRIC.

Specification forming part of Design No. **6,889**, dated September 16, 1873; application filed August 25, 1873.
[Term of Patent 7 years.]

To all whom it may concern:

Be it known that I, THOMAS LANGHAM, of the city and county of Philadelphia, State of Pennsylvania, have invented a Design for Knitted Fabric, of which the following is a specification:

The figure in the accompanying drawing fully illustrates my design for a knitted fabric, the principal features of which are the ribs *a* and bars *b*, alternated as shown.

The ribs *a* project outward from the face of the fabric, and give the latter a full appearance, while the bars *b* are composed of plain flat knitted loops, ornamented by a zigzag

thread, *x*, of a shade or color differing from that of the body of the fabric.

Irrespective of the colors employed, I claim—

The design for a knitted fabric, as described and represented in and by the accompanying drawing.

In testimony whereof I have signed my name to this specification in the presence of two subscribing witnesses.

THOMAS LANGHAM.

Witnesses:

WM. A. STEEL,
HARRY SMITH.
